SECTIONAL BLADE INK FOUNTAIN FOR PRINTING PRESSES

Harry W. Faeber, Larchmont, N. Y., assignor to
Time, Incorporated, New York, N. Y., a corpora-
tion of New York

Application February 8, 1949, Serial No. 75,238

6 Claims. (Cl. 101—365)

1

The present invention relates to a new and improved mechanism for controlling the metering or discharge of inks from printing press ink fountains, the invention covering more particularly the fountain blade structure and the manner in which its position is adjusted.

Great difficulty has always been experienced in effectively controlling the uniformity of the film of ink on the fountain cylinder of printing presses, and an object of this invention is to provide a new and improved adjusting mechanism for the blades of the fountain cylinders whereby careful control of ink delivery can be attained.

Another object of this invention is to provide an indicating means whereby it is possible to accurately reset the fountain blade to a desired position.

These objects, as well as others will appear from the following detailed description of a mechanism in which the invention has been embodied, taken in conjunction with the accompanying drawings, in which

Figure 1 is a fragmentary view in front elevation showing a device constructed according to the present invention;

Figure 2 is a view in longitudinal section of the fountain blades shown in Figure 1, taken on line 2—2 of Figure 1, and looking in the direction of the arrows; and

Figure 3 is a view in end elevation of the roller adjustment mechanism, taken on line 3—3 of Figure 1, and looking in the direction of the arrows.

With reference to Figures 1 and 2 of the drawings, the invention will be seen as embodied in an ink fountain 10 of conventional form, the fountain structure including a rear fountain wall 11 and bottom wall 12, a reinforcing web 13 being formed on the bottom wall to provide sufficient strength.

The fountain is completed by a fountain roller 14 which is mounted in a manner to be described and mounted for rotation in a suitable fashion, also in accordance with conventional practice.

In order that the film of ink carried from the fountain by the surface of the fountain roller may be suitably controlled, a plurality of blades 15 are provided upon the bottom wall 12. The blades 15 are formed with doctoring edges 16, which by their position with respect to the fountain roller 14, control the thickness of the ink carried by the fountain roll as it emerges from the fountain. It will be seen that the fountain is provided with a plurality of blades, as illustrated in Figure 1, these blades actually forming the bot-

2

tom surface of the ink receptacle adjacent the fountain roller 14.

The positioning of the respective blades 15 is controlled by a mechanism presently to be described, a cover plate 17 being provided to co-operate with the plurality of blades 15 to form a continuous bottom surface carried by the bottom plate 12. The forward extremity of the cover plate 17 may be provided with a seal 18 in order that leakage of ink between the cover plate 17 and blades 15 may be prevented. In the under-portion of the cover plate 17, a cavity 19 is formed, this cavity terminating in an end wall 20 in which apertures 21 are formed to receive control rods 22, one rod being provided for each of the blades 15. The ends of the rods 22 are threaded into the adjacent ends of the blades 15 as illustrated at 23, and coil springs 24 are carried upon the rods 22, these springs being seated 20 against the wall 20 and the ends of the respective blades 15 and serving to urge the blades 15 outwardly and to take up backlash that might exist in the threaded connection 23.

The outer extremities of the rods 22 are provided with manually operative knobs 25 having dials 26 formed thereon to facilitate the adjustment and indexing of the respective fountain blades 15. The rods 22 are supported in an end plate 27, being anchored against axial movement 30 by spring clips 28. It will be noted that the rear wall 11 is apertured at 29 in order that the rods 22 may extend therethrough as illustrated in Figure 2.

The cover plate 17 is secured in position by means of bolts 30 that are threaded at 31 into the cover plate and, at their other extremities, are provided with nuts 32 which bear against washers 33 against which springs 34 seat. The washers 33 are provided with cylindrical spring 40 covers 35 that are received within recesses 36 formed in the underside of the fountain bottom plate 12. By means of this structure, the cover plate 17 may be clamped securely in the position illustrated in Figure 2, the spring 34 serving to 45 maintain it in this position yieldingly.

In order that the fountain roll 14 may be adjusted properly in relationship to the other rollers of the ink distribution system (not shown), the fountain roll 14 is shown as being 50 provided with a shaft 37 that is journaled in a bearing 38 carried upon a plate 39 which is secured to extension 40 of fountain body 12. Bolts 41 are provided for securing the plate 39 to extension 40 and this assembly is mounted 55 upon side frame 42. Bolts 43 are provided to

secure the extension 40 to the side frame 42, enlarged recesses 44 being formed in the extension 40 in order that the position of the entire fountain assembly with respect to the side frame 42 may be adjusted. The same adjustable mounting is provided on the opposite end of the fountain assembly, where it rests on the opposite side frame, so as to allow independent adjustment of either end of the fountain roll and thus align it properly with the other rolls (not shown). Key 45 which is fastened to side frame 42 is adapted to be received in groove 56 formed in the underside of fountain body extension 40, thus permitting adjustment of the fountain assembly in either direction, transverse to the axis of shaft 37. Adjustment of this position is controlled by means of a screw 46 that is threaded into the extension 40 and the head 47 of which is formed with slot 48 which receives a stationary fork arm 49 formed upon the frame 42. Turning of the screw 46 in either direction thus moves the fountain assembly in a corresponding direction, the screws 43 being loosened to permit such movement and then secured in clamping position when the proper adjustment of the fountain assembly has been effected.

Rotation of the shaft 37 intermittently may be accomplished by suitable mechanism indicated generally at 50. Such mechanism is of conventional type and forms no part of this invention and, therefore, need not be described in detail herein. It will be observed that the shaft 37 is formed with a head plate 51 that is adapted to be received within a recess 52, formed in the adjacent end of the fountain roll 14. Bolts 53 may be provided to secure the head plate to the end of the roll, and this roll assembly is received in fountain end walls 54 in accordance with standard practice, a lubricating connection 55 being provided, as illustrated in Figure 1.

While the invention has been described with specific reference to the structure shown in the accompanying drawings, it is not to be limited save as defined in the appended claims.

I claim:

1. Inking mechanism for printing presses comprising an ink fountain having a bottom plate, end walls and a rear wall, a fountain roller rotatably mounted between the end walls, a plurality of fountain blades mounted upon the bottom plate and laterally abutted to extend between the end walls and having edges in operative relationship with said roller, a cover plate separate from the bottom plate, end walls and rear wall of the fountain, said cover plate being mounted to overlie the blades, spring means for urging said cover plate downwardly against the blades, and spring means reacting between said blades and cover plate to urge the blades in the direction of the fountain roller and the cover plate in the direction of the rear wall, and screw means operable in conjunction with said spring means for controlling the axial position of the blades with respect to the fountain roller, said laterally abutted blades, cover plate, walls, and roller forming an ink reservoir.

2. Inking mechanism for printing presses comprising an ink fountain having a bottom plate, end walls and a rear wall, a fountain roller rotatably mounted between the end walls, a plurality of fountain blades mounted upon the bottom plate and extending between the end walls, a cover plate adapted to cooperate with the blades, said cover plate being separate from the bottom plate, end and rear walls, and blades of the ink

fountain, spring means for urging the cover plate downwardly against the blades, screw means to effect axial movement of each of the blades with respect to the fountain roller comprising a plurality of screws threaded one into each blade, and a plurality of springs one encircling each screw and reacting between said cover plate and each blade, to urge the cover plate against the rear wall of the fountain and to urge the blades forwardly in the direction of the roller to eliminate back lash in the said screws.

3. Ink mechanism for printing presses comprising an ink fountain and roller assembly and carrier means for said assembly whereby said roller may be moved transversely of its axis including a stationary supporting frame having a pair of spaced apart key ways running transversely to the axis of said roller, a pair of fountain extensions disposed one adjacent either extremity of the roller for carrying said fountain assembly and having grooves formed therein for receiving the respective key ways in a slidable mounting, said fountain extensions each having an enlarged recess and shoulders formed therein, screw means received in said recess and abutting said shoulders and threaded into the stationary support, shoulder means affixed to said stationary support, and adjusting screw means reacting between said supporting frame and fountain extensions to move the fountain assembly in either direction on said key ways.

4. Inking mechanism for printing presses comprising an ink fountain having a bottom plate, end walls and a rear wall, a fountain roller rotatably mounted between the end walls, a plurality of fountain blades mounted upon the bottom plate and extending between the end walls, screw means to adjust the blades axially with respect to the fountain roller, and a cover plate extending between the end walls to hold the blades on the bottom plate and engaging the upper surfaces of said blades to form an ink seal therewith, first spring means urging said cover plate against said blades and second spring means reacting between each blade and said cover plate, and cooperating with the said screw means to eliminate back lash.

5. Inking mechanism for printing presses comprising an ink fountain having a bottom plate, end walls and a rear wall, a fountain roller rotatably mounted between the end walls, a plurality of fountain blades mounted upon the bottom plate and extending between the end walls, means to adjust the blades axially with respect to the fountain roller, a cover plate adapted to cooperate with the blades, adjusting means for positioning each of the blades independently with respect to the fountain, and means for attaching the cover plate to the fountain comprising a screw threaded into the cover plate and extending through the bottom plate, a hollow core member having a supporting plate secured thereon adapted to receive and retain the screw, a spring encircling the screw and positioned by said supporting plate to provide tension between the bottom plate and the supporting plate and to urge the cover plate on the blades.

6. Inking mechanism for printing presses comprising an ink fountain having a bottom plate, end walls and a rear wall, a fountain roller rotatably mounted between the end walls, a plurality of fountain blades mounted upon the bottom plate and laterally abutted to extend between the end walls and spaced from the rear wall, a cover plate extending laterally between said end

walls having a forward portion overlying said blades, a trailing edge adjacent said rear wall and a transverse depending flange carried thereby adjacent the trailing edge to rest upon said bottom plate, said flange having apertures formed therein aligned with said blades; means to effect axial movement of each blade with respect to the fountain roller comprising a plurality of screws threaded one into each of the blades, each of said screws passing through an aperture in said flange and reacting against said rear wall, and a spring encircling each screw reacting between the corresponding blade and the flange on said cover plate; means for securing said cover plate to said bottom plate comprising at least one screw threaded into the cover plate and extending through the bottom plate, a nut threaded on said screw, and a spring encircling the screw reacting between the nut and the

bottom plate to urge the cover plate against the blades; and means forming a liquid seal between the cover plate and the blades between said end walls, said walls, roller, cover plate and laterally abutted blades forming an ink fountain for retaining printing ink.
